Primary Examiner—Pamela Burgess**[57] CLAIM**

The ornamental design for a theater seat garment-supporting apparatus with flexible strap, as shown and described.

DESCRIPTION

FIG. 1 is a front elevational view of the theater seat garment-supporting apparatus with flexible strap showing my new design;

FIG. 2 is a rear elevational view thereof;

FIG. 3 is a left side elevational view;

FIG. 4 is a right side elevational view;

FIG. 5 is a top plan view thereof; and,

FIG. 6 is a bottom plan view thereof; and,

FIG. 7 is an isometric view of the theater seat garment-supporting apparatus with flexible strap mounted to the back of a theater seat which is shown in broken lines for illustrative purposes only and forms no part of the claimed design.
